Primary Examiner — John Windmuller*Assistant Examiner* — Steven Czyz*(74) Attorney, Agent, or Firm* — Brinks Gilson & Lione(57) **CLAIM**

We claim the ornamental design for a dispenser, as shown and described.

DESCRIPTION

FIG. 1 is a perspective view of a dispenser of the present invention.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof.

FIG. 8 is a perspective view of the dispenser of FIG. 1, shown with an exemplary refill insert;

FIG. 9 is a front view thereof.

FIG. 10 is a rear view thereof.

FIG. 11 is a left side view thereof.

FIG. 12 is a right side view thereof.

FIG. 13 is a top view thereof; and,

FIG. 14 is a bottom view thereof.

The broken lines depict portions of the article that form no part of the claimed design.

1 Claim, 6 Drawing Sheets---
